UNITED STATES PATENT OFFICE.

EVERETT CABLE FURNAS, OF LIMA, OHIO.

OILING SLEEVE.

Application filed August 22, 1922. Serial No. 583,592.

To all whom it may concern:

Be it known that I, EVERETT C. FURNAS, a citizen of the United States, and a resident of Lima, in the county of Allen and State 5 of Ohio, have invented a new and Improved Oiling Sleeve, of which the following is a full, clear, and exact description.

This invention relates to an oiling sleeve for semi-elliptical springs and has for an object to provide an improved construction 10 capable of use on elliptical springs for automobiles and other vehicles.

Another object of the invention is to provide an oiling sleeve which is formed to 15 readily adapt itself to leaf springs with retaining clips thereon.

A still further object of the invention is to provide an oil sleeve for springs of the semi-elliptical type wherein a protecting 20 member is provided and an oiling pad arranged to receive oil from time to time without necessitating the removal of the sleeve.

In the accompanying drawing—

Figure 1 is an outside view of the sleeve 25 in a spread condition.

Figure 2 is a view similar to Figure 1 but showing the inside of the sleeve.

Figure 3 is a longitudinal sectional view 30 through Figure 2 approximately on line 3—3.

Figure 4 is a fragmentary side view of an elliptical spring with a sleeve embodying the invention applied thereto.

Figure 5 is a top plan view of the structure shown in Figure 4.

Figure 6 is a transverse sectional view 35 through Figure 4 on line 6—6, the same being on an enlarged scale.

Figure 7 is a sectional view through Figure 1 approximately on line 7—7, the same being on an enlarged scale.

Referring to the accompanying drawing by numerals, 1 indicates a covering body which is preferably provided with turned over flaps or edges 2 and 3, said edges including the ends of a number of bendable metallic ribs 4. These ribs act as stiffening and holding members for holding the sleeve in place as indicated in Figures 4 to 6. The ends of these bendable metallic ribs may 45 be clamped in place by suitable clips 5. A pad 6 is arranged interiorly of the covering body 1, said pad consisting of two or more layers of oil absorbent material. This pad is held in place by suitable lines of stitching 50 arranged on opposite sides of the respective bars 4. It will be noted that some of

the layers of the pad 6 are arranged on opposite sides of the bars 4 and, consequently, when the stitching 7 is placed in position the bars are thereby positioned in the passageways in the pad. This will prevent the pad from moving longitudinally of the sleeve.

In order to provide oil from time to time when the device is in its use, a tubular member 8 is secured to the body 1 and pad 6 in 60 any suitable manner, said tubular member being provided with a cap 9 preferably threaded in place. Whenever it is desired to provide oil for the pad 6, cap 9 is removed and the desired quantity of oil supplied after which the cap is placed in position.

The sleeve is manufactured in a flat position as shown in Figures 1, 2 and 3 and when it is placed on the spring of an automobile, the center of the covering body 1 is laid on top of the spring and the remaining part of the sleeve is bent around the spring so as to completely enclose the same as indicated in Figure 6. The bendable bars 75 4 are bent and press tightly against the spring so that the pad 6 will be in continual engagement with the spring and thereby provide proper lubricant to the spring. It will be noted that the bars 4 not only 80 strengthen and hold the parts of the sleeve in proper position but also act as clamping or retaining means for holding the sleeve properly on the spring. Some springs are provided with clips 10 having bolts 11 at 85 the upper part. These clips are provided to prevent undesirable separation of the springs under some circumstances. When a clip, similar to clip 10 is used, the covering body is provided with tucks 12 and 13, 90 which tucks are properly stitched down except at points 14 and 15. This allows for extra material at these points to take care of the extra thickness and projection of the clip 10 and its retaining bolt 11. However, 95 on some types of springs where the long or main leaf is on the bottom, it is usually not necessary to provide these tucks but on the contrary to cut openings in the bottom of the sleeve to accommodate the bolt and nut 100 on the retaining clip.

After a spring has been properly lubricated, the sleeve shown in Figure 1 is provided with proper lubricant for the pad 6 and then the sleeve is wrapped around the spring as indicated in Figure 4. It will be noted that this provides a supply of lubri- 110

cant for the spring which will be necessary. It will also be noted that the water-proof covering of body 1 will keep the parts dry and substantially free of dust so that the 5 spring is always in good working condition and will only need lubricant at long intervals of time, which lubricant may be supplied through the tubular member 8.

What I claim is:—

- 10 1. An oil sleeve for a semi-elliptical spring, comprising a body covering of water-proof material extending for substantially one-half the length of said spring, a pad arranged in said covering and extending substantially 15 the full length thereof, and bendable members connected with said covering for holding the covering and pad in operative position around the spring.
- 20 2. An oil sleeve of the character described, comprising flat sheet adapted to be bent to form an enveloping structure, and a plurality of bendable bars connected with said sheet adapted to be bent with the sheet around a spring when the enveloping structure is placed on the spring whereby said bendable members act as retaining means for the sheet.
- 25 3. An oil sleeve for semi-elliptical springs, comprising a covering body of water-proof material, said body being formed with a pair of spaced plaits, said plaits being left unstitched at certain points for accommodating projections on the spring, a pad carried on the inner face of said body,

and means carried by the body for clamping the body and pad in position on the spring. 35

4. An oil sleeve for semi-elliptical springs, comprising an enclosing body, a pad arranged in said body, said pad being 40 adapted to receive and retain a quantity of oil for lubricating said spring, means forming an oil feed to said pad, and a plurality of independent bendable members for clamping said pad and enclosing member on said 45 spring.

5. An oil sleeve for semi-elliptical springs, comprising an outer covering, an inner member acting as an oil pad, said inner member being provided with rows of 50 stitching extending transversely and forming passageways, and a plurality of bendable members connected with said outer covering and extending through said passageways. 55

6. An oil sleeve for semi-elliptical springs, comprising a water-proof outer body, a plurality of bendable bars arranged interiorly of said body and extending transversely thereof, said bendable members being connected with the body adjacent the opposite edges thereof, a pad arranged on the inner face of said body with layers on opposite sides of said bendable members, and means for connecting said layers together in such a manner as to connect the pad to said bendable members. 60 65
